DESIGN FOR A SUPPORT FOR A SOAP TRAY
OR THE LIKE

Ferdinand A. Hilenski, Salem, Mass.

Application October 25, 1946, Serial No. 134,261

Term of patent 3½ years

(Cl. D4—3)

To all whom it may concern:

Be it known that I, Ferdinand A. Hilenski, a citizen of the United States, residing at Salem, in the county of Essex and State of Massachusetts, have invented a new, original, and ornamental Design for a Support for a Soap Tray or the like, of which the following is a specification, reference being had to the accompanying drawing, forming a part thereof.

The drawing is a perspective view of a support showing my new design.

I claim:

The ornamental design for a support for a soap tray or the like, as shown.

FERDINAND A. HILENSKI.
